WIRE-DRAWING EQUIPMENT

Lawrence F. Black, Donora, and Albert L. Kefover, Webster, Pa., assignors to The American Steel and Wire Company of New Jersey, a corporation of New Jersey

Application March 12, 1943, Serial No. 478,986

4 Claims. (Cl. 205—16)

This invention relates to wire drawing equipment and, particularly, to the wire drawing blocks of the vertical type having upstanding block pins, up which the wire coil grows from the block, with a ring, guided by the pins, engaging the top of the growing coil so as to be forced upwardly. If the operator does not stop the block in time, the coil grows up the pins so high as to cause the ring to disengage from the pins and present a hazard when it is thrown forcibly from them.

A specific example of the invention is illustrated by the following drawing:

Figure I is a top view;

Figure II is a side view;

Figure III is an enlargement from Figure I; and,

Figure IV is an enlargement, partly sectioned, from Figure II.

More specifically, the drawing shows the draw bench 1 and the vertical block 2 with its upstanding block pins 3, up which the wire coil 4 grows, along with the ring 5, guided by the pins 3, engaging the coil top. The ring 5 moves upwardly with the coil top as the coil grows. It is unnecessary to illustrate the block-powering electric motor and gearing, which are within the bench 1, the entire arrangement as so far described being conventional. As previously explained, and as is now obvious, the wire coil 4 can grow so large as to force the ring 5 from its guiding relationship with the pins 3, whereupon it is centrifugally thrown free, presenting a hazard to workmen in the vicinity.

According to the invention, an upstanding column 6 is fixed to the top of the draw bench 1; adjacent the block 2 with its pins 3, the column rising to above the top level of the pins 3, and its top mounting a control switch 7 for the motor inside the draw bench 1, this switch having an outwardly biased button 8 which must be constantly pressed inwardly to permit operation of the motor, release of the pressure permitting the button to move outwardly by reason of its bias, and stopping the motor powering the block 2. A collar 9 is fixed to the column beneath the switch 7, by a set screw 10, and this collar supports a bearing 11 rotating on the column 6. This bearing 11 mounts a clevis 12 in which a two-armed lever 13 is pivoted with a long arm extending over the top of the block 2, free from the pins 3, and a short arm extending into the clevis. The short arm of this lever 13, carries a bearing plate 14 which is biased upwardly by the weight of the long arm, the latter, consequently, being

biased downwardly. A retainer ring 15 is fixed to the column 6 above the bearing 11, by a set screw 16, and has a slot 17 in its bottom face in which the bearing plate 14 works vertically, the arrangement being such that this slot 17 cooperates with the bearing plate 14 to lock the lever 13 against lateral swinging, but permits lateral swinging of this lever 13, by rotation of the bearing 11 carrying the clevis, when the long arm of the lever 13 is raised sufficiently to drop the bearing plate 14 from the slot 17, it then being possible to swing the lever 13 laterally to beyond the side of the block 2 and pins 3, to permit removal of the ring 5 and the wire coil 4. When the lever 13 is swung back to above the block 2 and pins 3, it may again be lowered by reason of the bearing plate 14 rising into the slot 17, the latter functioning as a guideway in which the end of the bearing plate may play.

20 A finger lever 18 is pivoted to the top of the retainer ring 15 so that it swings in the same plane as the lever 13, it having a finger 18a capable of pressing against the button 8, and a short end cam portion 18b, on the other side of 25 its fulcrum, which bears on the top of the bearing plate 14 when the latter rises with its end in the guideway or slot 17. The cam portion 18b has a flat end which cocks in a canted position respecting the flap top face of the bearing 14, so that the finger 18a holds the button 8 inwardly against its outward bias, this position being maintained by the weight of the long arm of the lever 13 until this long arm is raised so as to slightly lower the plate 14, the cam end 18b then being 30 capable of snapping inwardly, toward the column 6, so as to permit retraction of the finger 18a and consequent outward movement of the biased button 8. When at this button-releasing position, downward movement of the long arm of the lever 13 cannot force the bearing plate 14 upwardly, because it is engaging the flat end of the cam end 18b substantially at right angles, movement of the finger lever 18 to the button-depressing position being possible only by the use of sufficient force to lift the long arm of the lever 13 or, perhaps more conveniently, by lifting the long arm of the lever 13, moving the finger lever 18 to button-depressing position and then releasing the long arm of the lever 13 so that its weight 40 forces the bearing plate 14 upwardly and holds the finger lever 18 in its position pressing the button 8 inwardly. It will be noted that when the lever 13 is swung away from over top the block it disengages completely from its association 45 with the finger lever, and that, therefore,

it cannot start the block motor even if it is inadvertently pressed downwardly.

The ring 5 is provided with a cross bar 19 which centrally carries a bearing plate 20, and the long arm of the lever 18 carries an adjustable collar 21 having a depending finger 22 which can be engaged by this bearing plate 20. When this occurs, the long arm of the lever 18 is raised, the finger lever 18 snaps to button-releasing position and the button 8 moves outwardly so that the switch 7 stops the motor powering the block 2.

In explanation of the operation of the invention, let it be assumed that the block 2 is being driven by the motor, inside the draw bench, and that a wire coil is growing upwardly along the block pins 3, the ring 5 traveling upwardly by reason of its engagement with the top of the growing coil. Until the coil grows to a considerable height the long arm of the lever 18 is free, it being prevented from falling by reason of the engagement between the bearing plate 20, on the short arm of the lever 18, and the cam end 18b, of the finger lever 18, the latter being, at this time, of course, in a position holding the button 8 inwardly so that the motor can run to power the block 2. Before the wire coil can grow to such a height that the ring 5 might be released from the block pins 3, the bearing plate 20, which naturally rises with the ring 5, engages the finger 22, depending from the collar 21, raises the long arm of the lever 18 and stops the motor powering the block 2, by reason of the cam end 18b of the finger lever 18 then being free to snap inwardly toward the column 6, it being understood that it is urged in this direction by the outward urge on the finger 18a exerted by the outwardly biased button 8. In this fashion the danger of the ring 5 being thrown dangerously from its engagement with the block pins 3, is positively avoided.

We claim:

1. The combination of a vertical wire drawing block, vertical block pins up which the wire coil grows from the block, a ring guided by the pins for engaging the top of the growing coil, a control switch for the block, and a lever system worked by the rising of the ring for operating the switch.

2. The combination of a vertical wire drawing

block, vertical block pins up which the wire coil grows from the block, a ring guided by the pins for engaging the top of the growing coil, an electric switch having an operating button biased against pressure, a finger lever for pressing the button, a downwardly biased arm connecting with the finger lever to cause it to press the button when the arm is lowered and to release it when the arm is raised, and means for interengaging the arm and the ring so the ring can raise the arm against its bias.

3. The combination of a vertical wire drawing block, vertical block pins up which the wire coil grows from the block, a ring guided by the pins for engaging the top of the growing coil, an electric switch having an operating button biased against pressure, a finger lever for pressing the button, a downwardly biased arm connecting with the finger lever to cause it to press the button when the arm is lowered and to release it when the arm is raised, means for interengaging the arm and the ring so the ring can raise the arm against its bias, the arm swinging over top the ring when working and laterally swinging to a position beyond the side of the ring, to permit removal of the latter, and disengaging from operative association with the finger lever when laterally swung to such a position.

4. The combination of a wire coil bundle accumulator, rotating means for continuously forming and feeding wire coil convolutions to one end of said accumulator to form a wire coil bundle supported thereby which continuously grows longitudinally thereof toward its other end as long as said feeding continues, a member providing an annular surface of approximately the same diameter as said bundle and mounted for substantially parallel engagement of said surface with the growing portion of said bundle and for movement by the growing movement of said portion in its growing direction, said member being biased toward said portion, a controller for said means having a movable operating element, and means for using the movement of said member to control said operating element when said member is moved by said growing movement a predetermined distance.
